UNITED STATES PATENT OFFICE.

CHARLES SMALLWOOD, OF WASHINGTON, NORTH CAROLINA.

WHIFFLETREE-CLIP.

SPECIFICATION forming part of Letters Patent No. 683,509, dated October 1, 1901.

Application filed May 31, 1901. Serial No. 62,642. (No model.)

To all whom it may concern:

Be it known that I, CHARLES SMALLWOOD, a citizen of the United States, residing at Washington, in the county of Beaufort and State 5 of North Carolina, have invented a new and useful Whiffletree-Clip, of which the following is a specification.

The invention relates to improvements in whiffletree-clips.

15 The object of the present invention is to improve the construction of whiffletree-clips and to provide a simple, inexpensive, and efficient one adapted to be securely fastened to a whiffletree without perforating the latter and capable of being readily removed therefrom.

A further object of the invention is to provide a clip of this character adapted to afford a firm support for a whiffletree-hook, to 20 hold the latter in proper position with relation to the whiffletree, and to prevent the hook from dropping out of engagement with the traces.

25 The invention consists in the construction and novel combination and arrangement of parts hereinafter fully described, illustrated in the accompanying drawings, and pointed out in the claim hereto appended.

In the drawings, Figure 1 is a perspective 30 view of a whiffletree-clip constructed in accordance with this invention and shown applied to a portion of a whiffletree. Fig. 2 is a longitudinal sectional view. Fig. 3 is a detail perspective view of the clip.

35 Like numerals of reference designate corresponding parts in all the figures of the drawings.

1 designates a whiffletree-clip consisting of a single piece of metal bent between its 40 ends to form upper and lower jaws 2 and 3 and curved to conform to the shape of a whiffletree 4, which may be of any desired configuration. The jaws of the clip are extended in advance of the whiffletree to provide ears 45 4 and 5, which are spaced apart to receive the shank 6 of a whiffletree-hook 7. The upper and lower jaws are provided with central openings 8, formed by diagonal cuts centrally crossing each other and providing triangular 50 tongues or projections 10, which are bent inward, as clearly illustrated in Figs. 2 and 3 of the accompanying drawings. These tongues

or projections form pointed spurs, which are embedded in the upper and lower faces of the whiffletree, being forced into the same by the 55 means hereinafter described, and they enable the jaws to firmly grip the whiffletree and hold the clip securely in place against longitudinal movement in either direction. By this construction the clip is adapted to be 60 securely fastened to a whiffletree without perforating the same for the reception of a bolt or similar fastening device; but should the tongues or spurs after a long time become 65 worn down or broken a bolt may then be passed through the openings of the upper and lower jaws and through the whiffletree.

The ears 4 and 5, which are located in advance of the whiffletree, are provided with perforations 11 and 12 for the reception of a 70 bolt 13, which also passes through the shank of the hook. The bolt 13 is adapted to draw the upper and lower jaws together and force the spurs or projections into the whiffletree, and the clip is sufficiently resilient to spring 75 open and withdraw the tongues or spurs from the upper and lower faces of the whiffletree when the bolt 13 is removed. The upper perforation 11 of the ear 4 is rectangular to conform to the configuration of the adjacent portion of the shank of the bolt to prevent the latter from rotating and loosening the nut. The hook 7, which extends forward from the clip, has its bill 14 located directly over the shank and bent downward, as clearly shown 85 in Fig. 2, to confine a trace-chain or other connection in the hook and to prevent the latter from dropping out of engagement with the trace. The whiffletree-hook is pivotally mounted between the ears of the clip and is 90 adapted to swing horizontally to yield to the movements of the whiffletree.

Instead of pivoting a whiffletree-hook between the extended ears a ring or link or any other suitable device may be connected to a 95 whiffletree by the clip. The clip may be arranged either at the center or end of a whiffletree and can be advantageously employed for connecting a whiffletree to the beam of a plow.

It will be seen that the device is exceedingly simple and inexpensive in construction, that the inwardly-extending spurs or projections obviate the necessity of perforating the whiffletree, and that the clip is resilient and

is adapted to withdraw the spurs or projections when the bolt is removed.

What I claim is—

In a device of the class described, a clip
5 for whiffletrees provided with upper and lower
jaws having cuts crossing each other, the sev-
ered portions of the metal being bent inward
to provide alined openings and to form in-
wardly-extending pointed spurs or tongues
10 for engaging a whiffletree, said alined open-
ings being adapted to permit a bolt to be

passed through the clip, and a fastening de-
vice connecting the jaws and adapted to hold
the spurs in engagement with a whiffletree,
substantially as described.

In testimony that I claim the foregoing as
my own I have hereto affixed my signature in
the presence of two witnesses.

CHARLES SMALLWOOD.
